FISHHOOK COVER

Henry W. G. Jend, Grosse Pointe Park, Mich.

Application July 13, 1938, Serial No. 218,931

3 Claims. (Cl. 43—38)

The present invention relates to improvements in the art of fishing equipment and refers more particularly to devices or covers designed for fish-hooks and provides a device of this character

5 wherein a neatly formed case or pocket composed preferably of stainless steel is provided, or it may be made of a plastic material or the like.

It is a prime object of the invention to provide 10 a suitable guard or cover whereby the individual hook is entirely concealed, and whereby the barb of the hook is shielded or prevented from contacting any object while being thus protected, objects such as clothing and the flesh of human 15 beings and animals alike.

It is obvious that unprotected fish-hooks have 20 frequently caused very serious wounds because of the fact that the particular shape of the fish-hook renders them extremely difficult to remove from the object to which it is engaged. In fact 25 the fish-hook is designed so as to become rigidly fixed within the fish's mouth making it effective for the purpose, which is all the more reason why it should be protected from engagement with objects other than what it is intended for.

25 With the foregoing in mind, it will become readily apparent that the invention possesses further advantages, all of which will be clearly 30 revealed during the course of the following detailed description, illustrated throughout the accompanying drawing, and more fully pointed out in the appended claims.

With reference to the drawing:

35 All of the views in the drawing are drawn to the scale of twice size.

Figure 1 is a blank of the complete structure.

Figure 2 is a side elevation of the device after being properly formed.

Figure 3 is a section taken upon line 3—3 of Figure 1.

Figure 4 is a side elevation of the device in a horizontal position.

Figure 5 is a bottom view of the device in a horizontal position.

Figure 6 is an elevation of a conventional type 45 key ring showing a plurality of the devices accommodated thereon as indicated.

Figure 7 is a sectional view of the device showing a conventional type of fish-hook normally positioned therein.

50 In further carrying out the invention and with particular reference to Figure 1, the metal or material from which the device is made constitutes a blank as therein shown and which is foldable as upon the dotted line A and the finished article will appear as indicated in Figures 2, 4, 5 and 6 respectively.

When the device is completely formed the same has walls 1 which are disposed in spaced

apart relation, and space 2 intermediate said walls is thereby provided so as to slidably receive barbed end B of fish-hook C, and likewise release said hook at will.

5 Apertures 3 are provided where indicated within the respective walls 1 and are in axial alignment with respect to each other. The purpose of apertures 3 is to provide means whereby the device may be easily secured to key ring D at such time when desired, and as shown in 10 Figure 6, and it is noted therein that the average key ring will accommodate more than one of the devices for the purpose of convenience.

Referring now to Figure 2, each of walls 1 has semi-circular lower portion 4, and said portions 15 rising vertically and terminating to obliquely disposed doubled-back portion 5 as indicated.

In conclusion it is obvious that the device is 20 preferably composed of a relatively thin material, such as steel, plastic or the like and formed 25 from a single blank as indicated in Figure 1, however it may be casted of suitable metal or otherwise, and it should be further understood that the invention is not restricted to the geometrical proportions as outline in Figure 1, however any departure from these lines would of 25 course fall within the scope of the claims.

Having thus fully described my invention, what I claim as new is:

1. In a fish-hook cover composed of a blank, 30 said blank being deflected and doubled over through the vertical center thereof and forming thereby a pair of spaced apart walls, each of said walls being substantially semi-circular at the lower portion thereof and this portion rising 35 vertically therefrom and terminating to an obliquely doubled over portion.

2. In a fish-hook cover composed of a single blank, said blank being deflected in a manner so as to form a pair of walls of uniform proportions, and the space intermediate said walls being 40 adapted to detachably receive a fish-hook, each of said walls having an aperture therein and effecting an uninterrupted passage transversely through the device, said passage being adapted to permit the device to engage a key ring. 45

3. In a fish-hook cover, a unitary structure comprising a pair of walls disposed in spaced apart relation, the space intermediate said walls being adapted to slidably receive a fish-hook, each of said walls being arcuate at the lower end 50 thereof and rising vertically therefrom and terminating to an obliquely disposed doubled over portion, also each of said walls having an aperture therein, said apertures being in axial alignment with respect to each other so as to admit 55 the passage of a key ring therethrough.

HENRY W. G. JEND.
